UNITED STATES PATENT OFFICE.

ARCHIBALD L. GILLAM, OF SANDUSKY, MICHIGAN.

DIPPER EXCAVATOR.

1,120,806.

Specification of Letters Patent. Patented Dec. 15, 1914.

Application filed November 7, 1912. Serial No. 729,964.

To all whom it may concern:

Be it known that I, ARCHIBALD L. GILLAM, a citizen of the United States, residing at Sandusky, county of Sanilac, and 5 State of Michigan, have invented certain new and useful Improvements in Dipper Excavators, of which the following is a specification.

This invention relates to dipper excavators.

The present invention has for its object the provision of a novel excavator of the dipper type, particularly adapted for digging ditches or trenches in which sewer 15 pipes, tile, and the like may be laid, whether the ditch or trench is to be straight or curved and wide or narrow, which may be constructed at relatively small expense, will have few parts and be light, durable, strong, 20 and require but one man for its operation, while having an excavating capacity several times that of the ordinary trench, ditch, or other excavator heretofore known to the art.

Another object is the provision of a novel 25 excavator whose mechanism is so arranged and constructed that it may be readily moved from place to place and made ready for operation with the expenditure of a small amount of time and labor, and, further, which will be adapted to operate on 30 much softer ground than is possible with other excavators, and even to operate on marshy land or in water as a dredge, on account of the lightness of the machine and 35 the construction thereof whereby the entire dredging mechanism may swing from side to side through a relatively wide arc.

A still further object is to provide an excavator arranged and constructed in a novel 40 manner whereby it is adapted to retain itself in position on the ground rather than to tilt, as is the tendency of excavators whose dipper stem extends outwardly from the supporting frame, and which will also be 45 adapted to excavate through a relatively wide range, due to the position of the excavating mechanism in respect to the manner of support of the frame therefor.

My invention consists, first, of an improved 50 mounting for the swinging part of the excavator frame; second, an improved operating means for swinging the frame; third, improved means for supporting the swinging frame from the ground, as will 55 appear fully hereinafter.

In the accompanying drawings:—Figure

1 is a plan view; Fig. 2, an end elevation; Fig. 3, a detail view showing the supporting means and track.

The main frame 1 of the machine is of 60 open, substantially rectangular form so that the excavating mechanism can operate centrally thereof and the dipper and its stem pass freely up and down through the frame to excavate beneath it. The frame is suitably braced by crossed braces at its end parts which are located above the trucks 2 and 3 having ordinary traction wheels 4, providing means whereby the machine is supported only at its ends and may be moved 65 from place to place as the work progresses or for beginning another excavation.

The excavating mechanism is carried by the frame 1. I do not restrict myself to any special excavating mechanism provided 75 it is carried by frame 1 and is adapted to operate beneath said frame, and I have only shown so much of an excavating mechanism as will give a clear understanding of the operation of my invention. Pivoted to opposite sides of frame 1 at 5 are a pair of upwardly converging rockers 6; pivoted at 7 to frame 1 are an upwardly converging pair of rockers 8. The rockers 6 and 8 are pivoted at 9 and 10 to a dipper stem 11 which has a 80 dipper 12 which is raised and is operated by a power cable 13 running over a sheave 14 carried by an upwardly extending arm 85 15 supported by frame 1 and is operated by any suitable drum 16 driven by any suitable 90 motor. Under the control of the cable 13, the excavating dipper 12 passes up and down through the open frame 1, moving on the rockers 6 and 8 as its supports and moving at all times in the same vertical plane 95 which includes the stem 11. When the frame 1 is stationary, a straight ditch or trench can be dug by the dipper 12. Suitable chains 17, 18 and 19 coöperate with the rockers 6 and 8 to limit their movements.

The digging mechanism shown and described is the same as that set forth in the patent to Ruben Jury, No. 1076676, dated October 28, 1913, but I do not limit 105 myself to the use of this or any other digging mechanism.

The frame 1 is at one end pivotally mounted on a king bolt 20. The bolster 21 of the other end of the frame carries a 110 rigid arc-shaped support 22 which consists of a center rack 23 and tracks 24 flanking

said rack. The support 22 conforms to the arc of a circle whose center is the king bolt 20. Carried by the swinging end of frame 1 is a pinion 25 which meshes with the rack 23 and tends to prevent lateral shifting, except when purposely moved, of the frame 1. Carried by the frame 1 are pairs of supporting wheels 26, 27 which travel on the tracks 24 and perform the two-fold function of supporting the frame and of relieving the king bolt 20 of strain due to the operation of the dipper 12 when excavating. Secured to the bolster 21 are cables 28 and 29 which run over idler sheaves 30, 31 on the support 22 and thence over sheaves 32, 33 on the arm 15, from which they pass to a drum or drums 34 adapted to be driven by any suitable power. The drum or drums 34 let out one of the cables and take up the other, thereby causing the entire frame 1 and all of the mechanisms carried thereby to be shifted laterally on the bolt 20 as a pivot, enabling the dipper 12 to cover a wide range of lateral movement and permitting it to dig a ditch on a curve or to excavate a wide stretch of ground without lessening any of the advantages of excavating intermediate the points of support of the frame 1. I find it advantageous when the frame 1 is swung rather far to one side or the other, to support it in order to relieve the support 22 of undue strain, and I, therefore, prefer to provide legs or braces 35 pivoted at 36 and provided with feet 37 which may be let down and rest upon the ground. Any suitable means such as a spring clip or other fastener 38 may be provided on frame 1 for holding the legs in raised position when they are not needed.

Supported by the frame 1 is a double inclined chute 39 whose apex is disposed below the center of the dipper 12 when the latter is in discharging position and, consequently, the material contained in the dipper discharges by gravity down said chute in a divided stream and may be carried off to any desired point or loaded into any receptacle.

Assuming that the parts are in the position shown in Figs. 1 and 2, if the frame 1 be retained in that position and the excavating mechanism 6, 8, 11, 12, 13 be operated, it will work up and down through the frame 1 and dig a straight ditch, the dipper rising after each cut and discharging the contents on the chute. The machine may be advanced to continue the digging of a straight trench. If, however, it is desired to dig the ditch or trench on a curve, the cables 28 and 29 will be operated to sufficiently move the frame 1 to cause the dipper to dig the ditch

on the curve. If a ditch wider than the dipper 12 is to be dug, the cables will be operated to swing the frame 1 to one side or the other as may be desired. If it is desired to excavate a relatively wide stretch, the frame 1 is shifted by the cables to cause it to move to any desired lateral position.

Having thus described my invention, what I claim as new and desire to secure by Letters Patent, is:—

1. In an excavator, the combination with supporting means, of a frame supported by said supporting means and pivotally mounted, a stationary arc-shaped support carried by one of the supporting means and adapted to support the swinging part of the frame, sheaves carried by said arc-shaped support, operating means carried by the swinging frame, cables connected to the supporting means and running over the sheaves aforesaid and adapted to be taken up or let out by the operating means aforesaid, and excavating mechanism carried by the swinging frame.

2. In an excavator, the combination with supporting means, of a frame pivotally mounted on one of said supporting means, an arc-shaped support carried by the remaining one of the supporting means and provided with a rack on its upper face, a pinion carried by the swinging frame which meshes with the rack, pairs of supporting wheels carried by the swinging frame and bearing on the upper face of the arc-shaped support on opposite sides of the rack, means for swinging the pivoted frame aforesaid, and excavating mechanism carried by the swinging frame.

3. In an excavator, the combination with a swingingly mounted and supported frame, of excavating mechanism carried thereby adapted to operate below the frame and intermediate the points of support thereof, and legs or braces carried by the swinging frame and adapted to be let down to engage the ground.

4. In an excavator, the combination with supporting means, of other supporting means provided with an arc-shaped support, a swinging frame pivoted to the first-named supporting means and mounted upon the arc-shaped support, and legs or braces carried by the swinging frame and adapted to be let down to engage the ground.

In testimony whereof, I hereunto affix my signature in presence of two witnesses.

ARCHIBALD L. GILLAM.
